UNITED STATES PATENT OFFICE.

PLINY CATUCCI, OF NEWARK, NEW JERSEY, ASSIGNOR TO A. F. MEISSELBACH & BROTHER, A CORPORATION OF NEW JERSEY.

DESIGN FOR A PHONOGRAPH-HORN SUPPORT.

41,499.

Specification for Design.

Patented June 20, 1911.

Application filed March 16, 1911. Serial No. 614,974. Term of patent 14 years.

To all whom it may concern:

Be it known that I, PLINY CATUCCI, a citizen of the United States, residing at Newark, in the county of Essex and State of New Jersey, have invented a new, original, and ornamental Design for Phonograph-Horn Supports, of which the following is a specification, reference being had to the accompanying drawing, forming a part hereof.

The figure is a perspective view of a horn support for use in connection with phonographs, talking machines, etc., which is designed to carry the amplifying horn in a convenient position relative to the phonograph record.

It consists of a circular base 1, from which the standard 2, extends upwardly and at a

slightly rearward incline. Upon the upper end of the standard 2, the elbow 3, is located, said elbow having the vertical upward extension 4, reduced at 5, to receive the horn connection, and the lateral extension 6, to receive the sound reproducing devices.

The configuration of the support is neat, simple and gives a pleasing and graceful finish to the entire structure to which it may be attached.

I claim:

The ornamental design for a phonograph horn support, substantially as shown and described.

PLINY CATUCCI.

Witnesses:

W. T. FIELDE,
LOUIS M. SANDERS.
